UNITED STATES PATENT OFFICE.

CLAUDE A. CONOVER, OF NEWBURGH, NEW YORK.

FIRE EXTINGUISHER.

Application filed June 21, 1921. Serial No. 479,265.

To all whom it may concern:

Be it known that I, CLAUDE A. CONOVER, a citizen of the United States, and a resident of Newburgh, in the county of Orange and State of New York, have invented a new and Improved Fire Extinguisher, of which the following is a full, clear, and exact description.

This invention relates to fire extinguishers and particularly to fire extinguishers for automobiles or other devices using internal combustion engines and has for an object to provide a construction which may be manually set and which will thereafter automatically operate in case of a fire in the vicinity of the device.

Another object in view is to provide a fire extinguisher for automobiles which may be arranged beneath the hood or at some convenient point and connected with control means arranged at different points whereby the extinguisher may be automatically operated by reason of fire at some point distant from the extinguisher itself.

A further object, more specifically, is to provide a fire extinguisher with means which will automatically hold the extinguishing fluid in a sealed container but will also automatically move certain parts of the container to cause a discharge of the fluid in case of fire without injuring the container.

In the accompanying drawing—

Figure 1 is a diagram showing one embodiment of the invention as applied to an automobile.

Figure 2 is an enlarged sectional view through the extinguishing member shown in Figure 1.

Figure 3 is a transverse sectional view through Figure 2 on line 3—3.

In using an automobile, oftentimes the engine or certain parts of the engine becomes heated and even fire occurs beneath the hood without the driver being aware of the same until some considerable damage has been done. In other devices where internal combustion engines are used, similar difficulties are present. Various fire extinguishing devices have been provided which will operate properly when actuated by the driver but will not automatically take care of the fire conditions within the hood.

In the present invention it is intended to present a device which will automatically take care of fire within the hood of an automobile regardless of whether the fire is at the particular point where the extinguisher member is placed.

Referring to the accompanying drawing by numerals, 1 indicates a conventional hood for an automobile and 2 a fire extinguisher member or tank adapted to discharge an extinguishing liquid 3 when operated, said liquid forming a smothering gas as soon as released. This liquid may be any of the common extinguishing liquids now on the market or a special liquid as preferred. The container 2 comprises a cylindrical body 3 as shown in Figure 2 having a series of apertures 4 near one end. It will be noted that the body of the container is provided with ends 5 and 6, end 5 being liquid tight while end 6 is also liquid tight on the edges but in the center permits the tube 7 to reciprocate. A comparatively weak spring 8 is positioned to rest on the bottom 5 and support a disk 9 which may be of metal or other suitable material and which in turn is provided with a gasket or ring 10 of cork or other suitable material which will maintain a tight joint and will also resist the action of the liquid 3. The ring or gasket 10 normally closes the openings 4 by reason of the fact that the spring 8 is sufficiently strong to hold the parts normally in the position shown in Figure 2 against the weight of the liquid 3. At the upper end of the container 2 a piston 11 is provided having a packing ring or gasket 12 of cork or other suitable material. A comparatively strong spring 13 acts against end 6 and against the piston 11 so as to force said piston downwardly toward end 5 whenever the piston 11 is released. As spring 13 is stronger than spring 8, it will force the piston downwardly when released and will force the disk 9 downwardly against the action of spring 8 until the liquid 3 is permitted to pass out the various apertures 4. These apertures are preferably small so that the liquid will come out in small streams and, consequently, will readily evaporate for producing a smothering gas.

The gas will not only act in the immediate vicinity of the container but will permeate

practically all parts of the hood and will reduce the supply of air to such an extent as to cause any fire within the hood to be choked or put out. This action is automatic and is performed quickly and effectively without requiring the attention of the driver or any other operator.

In Figure 1 a mechanism has been shown which will produce this automatic action. This consists in providing a support for the tube 7, which tube is rigidly connected with the piston 11 and is provided with a filling hole normally closed by plug 14. The upper end of the tube 7 is formed into a handle 15 so that it may be readily raised and the locking pin or catch 16 caused to snap into the aperture 17 provided in the upper part of the handle. The catch 16 is slidingly mounted in a suitable bracket 18 fixed in any suitable manner to the dashboard or other part of the automobile while a spring 19 acts against bracket 18 and against pin 20 for normally holding the catch 16 in engagement with the handle 15. The catch 16 is connected by a link or other suitable means 21 with the core 22 of solenoid 23 which solenoid is supported in any desired manner on the dashboard of the automobile or other suitable support. A battery 24 or other suitable source of electric supply 24 has one side connected to the solenoid 23 and the opposite side connected with a thermostat 25. The stationary contact 26 of the thermostat is connected through wire 27 to the solenoid 23 so that when the thermostat 25 is subjected to a certain rise in temperature, the circuit will be closed and solenoid 23 will become energized. This will cause a disengagement of the catch 16 from handle 15, and consequently, piston 11 will be released so that the spring 23 may force said piston downwardly and cause the liquid to be expelled through the spray holes 4.

In the drawing, only one thermostat 25 has been shown but it will be evident that any desired number could be connected up with the use of current and with the solenoid 23 so that in case a fire should occur at any point within the hood, the circuit will be closed and the liquid 3 discharged. It will be, of course, evident that the thermostat will act independently of any driver or other operator and may be set to close the circuit at any desired temperature. In the drawing only a conventional showing of thermostat has been illustrated but it will be evident that any suitable or preferred form of thermostat may be used.

What I claim is:—

1. A fire extinguisher of the character described, comprising a fire extinguishing fluid container provided with an annular series of openings adjacent one end thereof, means for normally closing said openings and spring-actuated means for causing said

covering means to be moved away from the openings and allow the fire extinguishing fluid in the container to be discharged through said openings.

2. A fire extinguisher of the character described comprising a container provided with openings in the sides and near the bottom but spaced from the bottom, a disk arranged in the container, a spring for holding said disk so as to close said openings, said container being adapted to contain fire extinguishing liquid, a piston arranged in said container adapted to press against the liquid, a spring for actuating said piston whereby the first mentioned spring is overcome and the disk moved away from said openings so that said liquid may flow therethrough, a catch for normally holding said piston against operation, and electrically operated means for moving said catch to a disengaged position, said means including a thermostat for closing the circuit.

3. A fire extinguisher of the character described comprising a tank provided with a number of openings therein, a closure for said openings, a spring for normally holding said closure over the openings, said container being adapted to contain a fire extinguishing liquid, means arranged in the container for pressing against the liquid and thereby forcing said closure away from said openings against the action of said spring, said means having a member extending to a point exteriorly of the container, a catch engaging said member, a solenoid adapted to move said catch to a disengaged position when energized, and a circuit for said solenoid, said circuit including a source of current and a pair of contacts, one of said contacts being carried by a thermostat.

4. A fire extinguisher comprising a liquid receiving container provided with openings, a spring pressed closure for said openings, a spring pressed piston acting on the liquid in the container for forcing said closure away from said openings whereby the liquid may be discharged through said openings, a spring pressed catch for normally holding said piston against movement, a solenoid for moving said catch to a disengaged position against the action of its spring, a pair of contacts, a thermostat for closing said contacts, and a circuit including a source of current, said contacts and said solenoid.

5. A fire extinguisher comprising a container adapted to contain fire extinguishing liquid, said container having apertures therein a short distance from the bottom, a partition disk arranged in said container, a cork ring arranged on said disk and acting as a packing ring, a spring for supporting said disk so that the packing ring thereof will normally cover said openings, a piston arranged in said container, a cork packing ring for said piston, a power spring

acting on said piston for moving the same when released so as to force said liquid downwardly until the first mentioned spring has been compressed sufficiently to permit the liquid to flow out said openings, a catch co-acting with said piston for normally preventing its movement under the action of

10 said power spring, a solenoid for moving said catch to a disengaged position, and a circuit for said solenoid, said circuit including a source of current, a pair of contacts and a thermostat for closing said contacts.

CLAUDE A. CONOVER.
